UNITED STATES PATENT OFFICE.

CHARLES A. JOHNSON, OF BODEGA, CALIFORNIA.

SHOE SOLE.

Application filed July 16, 1925. Serial No. 43,940.

This invention relates to improvements in shoe soles, my principal object being to provide a sole which is light, very durable, flexible, water proof, and an almost perfect non-
5 conductor of heat, cold and electricity.

My sole while light is quite thick, which prevents oils, acids or water from getting to the shoe.

The sole besides has inherent oil resisting
10 properties and will not deteriorate when exposed to oil, grease or water.

My sole is therefore particularly adapted for use by workers in canneries, laundries, tanneries, creameries, chemical works, oil refineries and any other places where the floor
15 is apt to be wet with various liquids.

Another object of my invention is to provide a sole which while having the above stated water proof features, is air ventilated
20 and will not sweat the feet as most composition soles do, and which cause numerous foot ailments to develop.

A further object is to provide a sole which may be marketed in a very few stock sizes,
25 since it is capable of being trimmed down to fit different shapes and sizes of shoe soles without preventing my sole from being properly attached to the shoe.

Many persons who have to work while
30 standing on cement and other hard floors develop numerous aches and pains in the feet and legs from so doing. Those who, working under such conditions, have worn my soles, report a lack of any such aches and
35 pains, or an almost immediate disappearance of the same. My sole is therefore especially adapted or use on cement floors, whether wet or dry.

A further object of the invention is to produce a simple and inexpensive device and yet one which will be exceedingly effective for the purpose for which it is designed.

These objects I accomplish by means of such structure and relative arrangement of
45 parts as will fully appear by a perusal of the following specification and claim.

In the drawings similar characters of reference indicate corresponding parts in the several views:—

50 Fig. 1 is a bottom plan view of my improved sole.

Fig. 2 is a side elevation of the same.

Fig. 3 is a longitudinal section thereof.

Fig. 4 is a fragmentary cross section on the
55 line 4—4 of Fig. 1.

Fig. 5 is a fragmentary cross section

through one of the sole grooves showing the method of attaching my sole to an ordinary shoe sole.

Referring now more particularly to the characters of reference on the drawings, the numeral 1 denotes the body of the sole of conventional contour and preferably formed of a composition of rubber, cork and other ingredients. The sole is of uniform thickness throughout except at its rear end, where it is reduced in thickness from its outer face for a certain distance transversely to form a ledge 2.

The outer face of the main portion of the sole is deeply grooved at various places. One such groove 3 is disposed transversely of the sole a short distance from the ledge 2 and extends from edge to edge of the sole. Another groove 4 extends longitudinally from the groove 3 to the tip of the sole and is disposed centrally of the shoe. The groove 4 is intersected by a transverse groove 5 disposed intermediate groove 3 and the tip of the sole, said groove 5 also extending to the side edges of the sole. The grooves 4 and 5 are preferably cut up into a number of separated sections by webs 6 which are the same thickness as the sole. Other grooves 7 extend from the outer edge of the sole on each side of the groove 4 at an angle thereto, the inner ends of the groove 7 being preferably separated from the other grooves.

These various grooves, whose location may be altered somewhat as may be desired, serve two main functions. They not only form air vents allowing air to penetrate along the sole, but by lessening the thickness of the sole make the same more flexible than would otherwise be the case.

At various places between the grooves, the sole is provided with sockets 8 to receive non-skid plugs 9 of canvas or the like which extend to the outer surface of the sole.

The bottoms of the grooves, as well as the ledge 2, are provided with blind holes or sockets 10 at various intervals, while the bottoms of all the grooves are undercut on both sides as shown at 11.

The holes 10 are for the purpose of receiving screws 12 or the like by means of which my sole may be attached to the ordinary sole 13 of a shoe. Such screws when being placed are pressed through the thin webs between the bottom of the holes 10 and the adjacent faces of the sole, which webs then close firmly around the screws, since

the material of the sole is resilient or elastic. In this manner the water-tight feature of the sole is maintained. The reason for not punching all the holes all the way through at first or when the sole is made is that all holes may not be utilized and by making the holes blind the water tightness of the sole is conserved regardless of the nonuse of any of the holes.

10. The under-cuts 11 of the grooves enable metal strips or washers 14 (see Fig. 5) to be inserted to form rigid abutments for the heads 15 of the screws, which would otherwise sink into the sole and probably 15 pull through the same.

The grooves are deep enough so that the screw heads are below the outer face of the sole, preventing contact of the heads with the floor.

20. It will be noted that the non-skid plugs do not extend entirely through the sole. This is done purposely to avoid the decrease in resiliency which would otherwise be had. Also the sole is maintained as a shock-absorbing member throughout its entire area.

25. As a result of the various features of my sole as above described, my soles are truly

health soles, giving relief and comfort to all who wear them.

From the foregoing description it will be 30 readily seen that I have produced such a device as substantially fulfills the objects of the invention as set forth herein.

While this specification sets forth in detail the present and preferred construction 35 of the device, still in practice such deviations from such detail may be resorted to as do not form a departure from the spirit of the invention, as defined by the appended claim.

Having thus described my invention what 40 I claim as new and useful and desire to secure by Letters Patent is:—

A shoe sole comprising a body member, having in its outer face a plurality of spaced and relatively deep grooves open to the sides of the sole, the bottoms of said grooves being provided with a plurality of holes extending toward the inner face of the body; the sides of said grooves being undercut 45 along their bottoms, and washer elements 50 to extend across the grooves and fit in the undercut portions thereof.

In testimony whereof I affix my signature.
CHARLES A. JOHNSON.
